US0D1057243S

(12) **United States Design Patent** (10) **Patent No.:** **US D1,057,243 S**
(45) **Date of Patent:** **** Jan. 7, 2025**

(54) **FLASHLIGHT**

- (71) Applicant: **Energizer Brands, LLC**, St. Louis, MO (US)
- (72) Inventors: **Joanna Lynn Celestina**, Willoughby, OH (US); **Eric Chan**, Tsuen Wan New Territories (HK)
- (73) Assignee: **Energizer Brands, LLC**, St. Louis, MO (US)

(**) Term: **15 Years**

(21) Appl. No.: **29/865,061**

(22) Filed: **Jul. 6, 2022**

(51) LOC (15) Cl. **26-02**

(52) U.S. Cl.

USPC **D26/45**

(57) **CLAIM**

The ornamental design for a flashlight as shown and described.

DESCRIPTION

FIG. 1 is a top front perspective view of a flashlight according to the present design.

FIG. 2 is a bottom rear perspective view of the flashlight of FIG. 1.

FIG. 3 is a front view of the flashlight of FIG. 1.

FIG. 4 is a rear view of the flashlight of FIG. 1.

FIG. 5 is a left side view of the flashlight of FIG. 1.

FIG. 6 is a right side view of the flashlight of FIG. 1.

FIG. 7 is a top view of the flashlight of FIG. 1; and,

FIG. 8 is a bottom view of the flashlight of FIG. 1.

The broken lines in the drawings immediately adjacent the shaded surfaces depict the bounds of the claimed design and form no part of the claimed design. All remaining broken lines depict portions of the flashlight that form no part thereof.

1 Claim, 8 Drawing Sheets
